UNITED STATES PATENT OFFICE.

CHARLES W. HUTCHINSON, OF NEW ROCHELLE, NEW YORK.

BURGLAR-PROTECTIVE APPARATUS.

1,409,721.

Specification of Letters Patent. Patented Mar. 14, 1922.

Application filed April 11, 1921. Serial No. 460,563.

To all whom it may concern:

Be it known that I, CHARLES W. HUTCHINSON, a citizen of the United States, and a resident of New Rochelle, county of Westchester, State of New York, have invented certain new and useful Improvements in Burglar-Protective Apparatus, of which the following is a specification.

This invention relates to theft prevention devices and is particularly adapted to be used as a means for protecting merchandise or articles such as are usually displayed in show windows, although not restricted to such use, it being also adapted for use as a means for protecting bank tellers and others who, by reason of the nature of their employment are subjected to burglar attacks or attempted robberies.

An important object of the invention is to provide, in a device of the character described, a means whereby the device as a whole may be set into positive operation automatically upon the movement of certain co-operative elements thereof into tripped positions.

A further object of the invention is to provide a device of the above mentioned character which is strong, durable, simple in construction, and reliable in operation.

Other objects and advantages of the invention will become apparent from the following description taken in connection with the accompanying drawings in which;

Figure 1 is a front elevation of the device embodying my invention, the same being shown as installed in operative position.

Figure 2 is an end elevation of the device.

Figure 3 is an enlarged view in elevation of a portion of the device showing in detail the trip mechanism.

Figure 4 is an end elevation of that portion of the device shown in Figure 3.

In the drawings, wherein for the purpose of illustration is shown the preferred form of my invention, the numeral 5 indicates the base portion of a show window with which the device is particularly adapted to be used, the window being provided with a front glass plate 6 and end glass panels 7.

The device embodying my invention is adapted to be readily installed within a show window, and is supported in operative position by means of a pair of vertical uprights 8 and 9, the uprights being provided

with base portions 10 and 11 respectively, which are secured to the base 5 by any suitable means such as screws 12 or the like.

To the uprights 8 and 9 there is journaled a horizontally disposed shaft 13, one end of which is provided with a gear 14 meshing with a pinion 15 rotatably mounted upon a stud 16. The pinion 15, as clearly shown, is maintained in engagement with an operating gear 17 which, as will hereinafter appear, functions also as a ratchet wheel. The gear 17 is secured to the shaft 18, which is journaled on the upright 8, and provided at one end with a square shank 19 adapted to receive an operating handle 20. The operating handle 20 may be permanently secured to the shank 19 or may be removable therefrom, and is utilized as a means for rotating the shaft 13 through the instrumentality of the gears 14, 15 and 17 when placing the several co-operative elements of the machine in position to be actuated upon the attempt of a burglar to gain access to the show window.

To the upper ends of the uprights 8 and 9 there is pivoted by means of bosses 20' a pair of vertical bars 21 which are adapted to be moved from the full line position shown in figure 4 to the dotted line position shown therein.

The bars are limited in their movement in one direction by means of lugs 22 carried by the vertical uprights 8 and 9, and in their movement in an opposite direction by means of a wing or stop 23 which is secured to one of the vertical bars 21 and bent into the plane of the upright 8. One of the bars 21 is provided with a pawl 24 which is rigidly secured thereto and adapted to be moved into and out of engagement with the gear 17, serving as a ratchet wheel, when the bars 21 are moved respectively from the dotted line position shown in Figure 4 to the

full line position shown therein, and vice versa. To the lower ends of the vertical bars 21 there is suitably secured a horizontally disposed cross bar 25, the bar 25 being adapted to support a plurality of vertically disposed pickets 26 arranged in a spaced relation with respect to each other, as shown in Figure 1, and secured at their upper ends to a longitudinally disposed rail 27 rigidly secured to the upper ends of the vertical bars 21. The vertically disposed bars 21 together with the horizontally disposed

cross bar 25, and the longitudinally disposed rail 27 when taken collectively constitute a guard G which as is apparent is adapted to be moved from a vertical position to a slightly inclined position as illustrated in Figure 4.

The shaft 13, rotatably mounted within the uprights 8 and 9, serves as a drum adapted to receive thereupon a flexible curtain or guard, indicated as a whole by the numeral 28, the curtain or guard comprising a plurality of preferably metallic plates 29, flexibly connected together by means of suitable cables or the like, as shown at 30, which are threaded through openings 31 provided in the metallic plates.

As a means for automatically elevating the curtain or guard 28, I provide, working in a co-operative relation with certain other elements hereinbefore described, flexible cables 32 which are passed over guide pulleys 33 secured to a suitable support, such as a ceiling or the like, the cables 33 being adapted to support weighted elements, one of which is shown at 34 in Figure 2. The weighted elements 34, as is apparent, when released by reason of the disengagement of the pawl 24 with the gear or ratchet wheel 17, descend, and by reason of the connection of the cables 32 with the curtain or guard 28, the guard is unrolled from the shaft 13, which serves as a drum therefor, and is lifted to obstruct the entrance of a burglar after having attempted to enter by breaking the front glass plate 6.

The device embodying my invention and hereinbefore described is particularly adapted to be installed within show windows without detracting from the general appearance of the window and, under normal conditions, the various co-operating elements of the device are positioned as shown in the accompanying drawings. With the several elements of the device in their operative positions, as shown, the device as a whole may be set into operation by an obstacle moved into contact with the pickets 26 with such force as to cause the guard G to be moved to the position shown by the dotted lines of Figure 4. By moving the guard G to the position shown in dotted lines in Figure 4, the pawl 24 is released from the gear or ratchet wheel 17, whereupon the weighted elements 34, being thereby released, act through the flexible cables 32 to unroll the curtain or guard 28 from its shaft or drum 13, moving the same into a vertical plane, in which position the entrance of one attempting to gain access to the window is effectively prevented.

It is to be understood that the form of my invention shown and described herein is to be taken as a preferred example of the same and that various changes in the size, shape and arrangement of elements may be re-

sorted to without departing from the spirit of the invention and the scope of the subjoined claims.

I claim:

1. A theft preventive device comprising a drum, a curtain rolled upon said drum, means for unrolling the curtain from said drum and lifting the same to an elevated position, means for locking the curtain against unrolling, and a pivotally supported guard cooperatively associated with said locking means and adapted to be moved to release said locking means whereby said curtain is unrolled by the first named means.

2. A theft preventive device comprising a drum, a curtain rolled upon said drum, means tending to unroll the curtain from said drum, a movable guard, and means for locking said curtain against unrolling, the latter named means being actuated upon movement of said guard in one direction to release the curtain whereby it is unrolled from said drum by the first named means, and further actuated upon movement of said guard in an opposite direction to lock the curtain against unrolling.

3. A theft preventive device comprising a drum rotatably supported, a ratchet wheel co-operatively connected to said drum, a curtain rolled upon said drum, means tending to unroll the curtain from said drum, a pivoted movable guard adapted to be moved in opposite directions about its pivots, and means for engaging said ratchet wheel whereby said curtain is locked against unrolling, when said guard is moved in one direction and releasing said ratchet wheel when said guard is moved in an opposite direction to release the curtain whereby it is unrolled from said drum by the first named means.

4. A theft preventive device comprising a drum, uprights rotatably supporting said drum, a curtain rolled upon said drum, means tending to unroll the curtain from said drum, a ratchet wheel co-operatively connected with said drum, a movable guard pivotally connected to said uprights, and means engaging said ratchet wheel for locking said curtain against unrolling, the latter named means being adapted to be released from said ratchet wheel upon the movement of said guard whereby said curtain is unrolled from said drum by the first named means.

5. A theft preventive device comprising a drum, uprights rotatably supporting said drum, a gear carried by said drum, a second gear co-operatively connected with the first named gear, a curtain rolled upon said drum, means tending to unroll said curtain from said drum, a pawl engaging the second named gear for locking said drum against rotation, and a movable guard pivotally connected to said uprights, said guard being

adapted to be moved in one direction to release said pawl from the second named gear for unlocking said drum whereby said curtain is unrolled by the first named means.

- 5 6. A theft preventive device comprising a drum, means for rotatably supporting said drum, a pivotally supported movable guard, a gear carried by said drum, a curtain rolled upon said drum, means tending to unroll 15 the curtain from said drum, and means co-operating with said gear for locking said

drum against rotation, the second named means being actuated upon the movement of said guard in one direction to unlock said drum whereby the curtain is unrolled therefrom by the first named means and further actuated upon movement of said guard in an opposite direction to lock said drum.

In testimony whereof, I have affixed my signature to this specification.

CHARLES W. HUTCHINSON.
